Inventor

Henry L. Rowell.

UNITED STATES PATENT OFFICE.

HENRY L. ROWELL, OF DAYTON, OHIO, ASSIGNOR TO GEORGE W. HOLDEN,
OF SAME PLACE.

HINGED SLATE.

SPECIFICATION forming part of Letters Patent No. 224,306, dated February 10, 1880.

Application filed June 30, 1879.

To all whom it may concern:

Be it known that I, HENRY L. ROWELL, of Dayton, in the county of Montgomery and State of Ohio, have invented a new and useful Improvement in Folding Slates, of which the following is a specification.

The invention relates to the manner of hinging the frames, which is done by an elastic web the edges of which are held in metallic strips secured in slots of the frame by pins passing through the same.

The accompanying drawings are made part of my specification, and like letters of reference on the different figures designate like parts.

Figure 1 is a view of the folding slate fully opened. Fig. 2 is a side and sectional view of the flexible hinge.

A A represent slates constructed in the usual manner, the wooden frames of which are joined together by a flexible hinge, B, the hinges being held within mortises of the frame by pins which pass through the same. Cen-

trally between the sides of the frames are longitudinal mortises, indicated by dotted lines 25 at the upper hinge, and into these mortises are secured, as before specified, the flexible hinges.

In the construction of the hinge I use an elastic web, C. The edges are covered by metallic strips o, which are indented to secure them to the web. These are placed in the mortises, and are secured by pins passing through the frames and the metallic strips.

Having thus fully described my invention, 35 what I desire to secure by Letters Patent is—

As a new article of manufacture, a folding slate joined together by an elastic web, C, the edges of which are held in metallic strips o, and secured in the slots of the frames, sub- 40 stantially as described.

HENRY L. ROWELL.
